METHOD OF PRODUCING CUTBACKS

Thomas Robinson, Smithtown, N. Y., assignor to
 Lancaster Processes, Inc., Long Island City,
 N. Y., a corporation of New York

Application October 12, 1933, Serial No. 693,391

8 Claims. (Cl. 196—22)

This invention relates to cutbacks produced by treating relatively heavy viscous substances with a solvent or flux and is concerned more particularly with a novel method by which such materials can be made rapidly and at low cost. The method of the invention may be used to special advantage in the production of cutbacks of asphalt and coal tar pitch, and, therefore, for purposes of explanation, the details of the new method will be described in connection with the manufacture of asphalt cutbacks, although it is to be understood that the utility of the new method is not confined to the production of such materials, which are referred to merely by way of example.

15 Straight run asphalt produced by the distillation of asphaltic petroleum is too heavy and viscous for most purposes and it has been the practice heretofore to treat the asphalt with a solvent or flux to produce cutbacks which are used 20 in road making, for the production of asphalt paints, as roofing plastics, and for other purposes. The kind and quantity of the solvent or flux used in the production of a cutback depend on the asphalt to be treated and the characteristics of the final product desired, as for example, 25 in the production of asphalt cutbacks suitable for road making, the asphalt treated may have a melt point of 130° F. and the flux used may be a naphtha distilling between 150° F. and 450° F.

30 This flux may be mixed, for example, with the asphalt in the proportions by volume of 72 to 81 parts of asphalt and 28 to 19 parts of naphtha, and the materials are agitated in an open vessel until a uniform product is produced. In this 35 operation, a substantial amount of the solvent or flux is lost by evaporation, and as the material lost is made up of the more volatile constituents of the solvent, the solvent is thereby reduced in effectiveness and the length of the operation is 40 prolonged.

The present invention is directed to the provision of a method for producing cutbacks in which loss of the solvent or flux is greatly reduced so that the operations are shortened in 45 time and the cost of the final product is materially reduced. According to the new method, a quantity of finished cutback material is maintained in an intermediate storage chamber from which finished product is continuously delivered 50 to storage and material continuously withdrawn for circulation through a closed conduit which contains impelling and agitating means for maintaining the circulatory flow and effecting a violent agitation of the circulating material. The 55 asphalt to be treated and the solvent are continuously introduced into the conduit through the walls thereof and preferably, the asphalt and solvent are delivered into the conduit at diametrically opposite points and in line with impeller 60 and agitating elements therein.

In carrying out the new method, I prefer to use the apparatus disclosed in my copending application, Serial No. 693,392, filed October 12, 1933, although various other forms of apparatus may be employed. The apparatus of that application 5 is illustrated in the accompanying drawings, in which Fig. 1 is a vertical sectional view through the apparatus; and

Fig. 2 is a horizontal sectional view through the tubes of the apparatus containing the agitator 10 and impeller elements.

The apparatus illustrated includes an intermediate storage chamber 1 having a closed top provided with a discharge outlet 2 and at the bottom of the chamber, there is a discharge opening 3 through which material can flow downward into a hollow body 4, from the opposite sides of which lead two horizontal tubes 5. A shaft 6 carrying sets of impeller blades 7 spaced along it extends through the tubes and the body, and in 20 each tube there are two sets of blades, these blades being helically formed and so disposed that the blades in each tube operate to force liquid outward through the tube in a direction away from the body. Within each tube between the 25 blades are radial stator vanes 8 which extend inward from the tube walls and terminate close to the shaft. The outer end of each tube is connected to the bottom of the chamber by an upwardly extending conduit 9 and above each inlet 30 opening into the chamber is a plate 10 which overlies the opening and causes the liquid entering the chamber to flow helically upward therein.

The asphalt to be cut back and the solvent are 35 introduced into each disperser tube through diametrically opposed openings 11 in the tube walls and these openings lie in line with the first set of impeller blades in the tube, the ends of the blades terminating close to the inner wall of the tube 40 and each set having a dimension lengthwise of the tube which is at least as great as the diameter of the openings 11, as illustrated.

During the operation of the apparatus, a circulation of cutback material takes place, the 45 liquid leaving the bottom of the chamber and flowing down into the body. Liquid then flows from the body through each tube, and as the stream of liquid reaches the first set of blades in its tube, the stream is sub-divided into a plurality 50 of smaller streams, each lying between adjacent blades of the set. Heated asphalt in fluid condition flows continually into the tube at the periphery of the blades in the form of a stream and as the rapidly moving blades pass across the inlet 55 opening for the asphalt, sections of the asphalt stream are severed therefrom and mingled with the streams of cutback between the blades. The severing of the end sections from the asphalt stream by the mechanical shearing action of the 60

high velocity blades causes the asphalt to be broken up into fine particles which are thoroughly distributed through the small streams of cutback by the impact of the blades.

5 At the other side of the set of blades, the solvent is introduced into the streams of cutback between the blades in the same manner; that is, end sections are severed from a stream of solvent and the material in these sections is thoroughly mingled with the cutback between the blades at one side of the set. The solvent thus introduced dilutes the cutback in the streams into which it is delivered, while the asphalt fed into the other side of the tube enriches the cutback in the streams which it enters. As these enriched and diluted streams of cutback are forced out from between the impeller blades, the streams are united under conditions of great turbulence and the whirling liquid is subjected to hydraulic 20 shear and then enters the spaces between the radial stator vanes, where the motion of the liquid becomes rectilinear. The liquid then passes to the second set of impeller blades where it is violently agitated by the high velocity impact of the blades. After leaving the second set of blades, the liquid is discharged into the conduit which leads it back to the intermediate storage chamber. In the chamber, the streams of liquid from the two disperser tubes are deflected by the plates and caused to move along upward helical paths, the streams finally mingling so that a 30 more uniform product results.

As previously mentioned, the intermediate storage chamber is provided with a closed top having an outlet opening through which the finished material is continuously discharged at the same rate that asphalt and solvent to be treated are supplied and the use of the closed system in the apparatus prevents evaporation of the solvent. 35 The shaft extending through the tubes and carrying the impeller blades passes out through stuffing boxes at the ends of the tubes and the agitating operations are carried on under pressure resulting from the head of liquid in the intermediate 40 storage chamber and the pressure at which the solvent and asphalt are fed. Infiltration of air is, therefore, prevented and no air bubbles can enter the stream being treated so that the impeller blades operate at high efficiency. The effectiveness of the blades is also increased by the use of collars or other means on the shaft which, together with the tube walls, confine the stream being treated so that it has a thin annular form and is acted on only by the outer ends of blades 45 which travel at the highest velocity.

I have found that when the asphalt and solvent are subjected to impact and the shearing action of the high velocity blades at the points where these materials are introduced into the circulating stream of cutback, an excellent dispersion and mixing takes place so that the treatment of the asphalt with the solvent can be completed in a short time.

The production of cutbacks according to the new method can thus be carried on at a high output rate and without substantial loss of solvent. As compared with prior methods, my new method can be carried out with a saving up to 20% of the solvent, and since the proportion of the solvent saved includes those constituents of the solvent which are of the greatest volatility and effectiveness, the prevention of loss of the solvent not only reduces the cost of materials but also reduces

the total cost by the decrease in time of treatment.

What I claim:

1. A method of making a cutback of a viscous liquid substance which comprises creating a stream of previously produced cutback, introducing said substance into the stream by cutting end sections from a stream of said substance and mingling them with the cutback stream, introducing a solvent or flux into the cutback stream, and agitating the augmented stream. 5

2. A method of making a cutback of a viscous liquid substance which comprises circulating a stream of previously produced cutback, subdividing said stream, enriching one subdivision by introduction of said substance, diluting another sub-division by introduction of a solvent or flux, combining said enriched and diluted sub-divisions, into a single stream, agitating said stream, and continuously withdrawing a portion of said 20 stream from circulation.

3. A method of making a cutback of a viscous liquid substance which comprises separately introducing said substance and a solvent or flux into separate bodies of previously produced cut- 25 back, and thereafter mixing said separate bodies together.

4. A method of making a cutback of a viscous liquid substance which comprises creating a stream of previously produced cutback, introducing said substance into the stream by cutting end sections from a stream of said substance and mingling them with the cutback stream, introducing a solvent or flux into the cutback stream by cutting end sections from a stream of said solvent or flux and mingling them with the cutback stream, 30 35 and agitating the augmented cutback stream.

5. A method of making a cutback of a viscous liquid substance which comprises creating a stream of previously produced cutback, introducing said substance into the stream by cutting end sections from a stream of said substance and mingling them with the cutback stream, introducing a solvent or flux into the cutback stream 40 45 by cutting end sections from a stream of said solvent or flux and mingling them with said cutback stream, said substance and said solvent or flux being introduced into said cutback stream at points lying substantially in a plane transverse to the direction of flow of said cutback stream, 50 and agitating said augmented cutback stream beyond said plane.

6. A method of making a cutback of a viscous liquid substance which comprises separately introducing said substance and a solvent or flux into separate bodies of previously produced cutback, agitating said separate bodies, and thereafter, mixing said separate bodies together. 55

7. A method of making a cutback of a viscous liquid substance which comprises separately introducing said substance and a solvent or flux into separate bodies of previously produced cutback, agitating said separate bodies, and thereafter, mixing said separate bodies together and 60 subjecting the mixture to agitation.

8. A method of making an asphalt cutback which comprises introducing heated asphalt into a body of previously produced cutback, introducing a solvent or flux into another body of previously produced cutback, and thereafter, mixing said bodies together. 65 70

THOMAS ROBINSON.
